FRACTIONATING COLUMN

Emmett L. Durrum, San Francisco, Calif., assignor to Shell Development Company, San Francisco, Calif., a corporation of Delaware

Application May 27, 1941, Serial No. 395,382

9 Claims. (Cl. 261—114)

The present invention relates to improvements in bubble tray columns, used in fractional distillation, stripping, absorption, etc. More particularly, it relates to improved bubble trays which are of simple construction and high efficiency.

In the past, it has been customary to equip bubble columns with bubble trays made up of numerous elements comprising, among others, individual risers and bubble caps. These elements are of such nature that they must be secured in place to the bubble tray by welding or other means and the fabrication of such trays requires large amounts of time and labor. In some cases, especially when dealing with certain materials, such as glass or plastics, the labor and technique of fabrication and assembly are such that bubble trays according to the old plan could be made either not at all or only under such difficulties as to make their fabrication as a practical matter totally impossible. In addition to this, conventional bubble trays, which are welded or otherwise fastened in towers, have the drawback that at the temperatures of operation they warp or even crack loose from the column due to stresses set up by unequal thermal expansion or contraction at operating temperatures.

It is an object of the present invention to provide a simple inexpensive bubble tray. It is another object to provide a bubble tray which is an expansible member and which is adapted to be readily fabricated from glass, plastics or metals by molding, casting, forging, stamping, etc. It is a further object to provide a bubble tray eliminating the conventional risers and bubble caps. Other objects will become apparent from reading the present specification.

The present invention comprises a bubble tray provided with downspout means comprising two plate elements arranged to co-act to provide a liquid seal upon the tray. The top plate element according to the present invention is formed to provide a plurality of raised portions thereof, near the bases of which perforations are provided through the plate. The bottom plate element is likewise composed of corresponding raised portions adapted to register with the raised portions of the top plate. Perforations are provided through the bottom plate within the area of the raised portion. The plate elements are so disposed with respect to each other that the openings in the bottom plate element are at a level above the openings in the top plate element and in this manner a liquid seal may be maintained upon the tray. The invention can

be better understood from a consideration of the drawings.

Figures I to V are views of one type of bubble tray embodying the essential elements of the invention.

Figure I is a quarter perspective view of a portion of the bubble tray with parts broken away.

Figure II is a top plan of a section of a bubble column equipped with said tray.

Figure III is a sectional elevation of a column showing two trays, including downspouts and their disposition with respect to each other.

Figure IV is a bottom plan of said column.

Figure V is a quarter elevation showing detail of a preferred type of top plate trough.

Figures VI to IX are views of another type of bubble tray according to my invention wherein the length of the path of liquid flowing across the plate is increased.

Figure VI is a top plan of a section of column employing this type of tray and is taken on line VI—VI of Figure VII at the point indicated thereon looking in the direction of the arrows.

Figure VII is a sectional elevation of a column showing three trays including downspouts and their disposition with respect to each other.

Figure VIII is a bottom plan section taken on line VIII—VIII of Figure VII at the point indicated thereon looking in the direction of the arrows.

Figure IX is a quarter perspective view of a portion of the bubble tray.

Figure X is a top view of a tray in which the elevated portions are arranged concentrically and parallel.

Figure XI is a cross section of a portion of the tray of Figure XII taken at the points indicated thereon looking in the direction of the arrows.

Figures XII to XIV are views of another type of bubble tray according to the present invention, wherein the spiral does not lie in a single horizontal plane.

Figure XII is a sectional elevation of a column showing trays of this type and their relationship to each other.

Figure XIII is a top plan of the peripheral downspout system of Figure XII taken at the points indicated thereon looking in the direction of the arrows.

Figure XIV is another top plan of the peripheral downspout system of Figure XII taken at the points indicated thereon looking in the direction of the arrows.

In Figure I, 20 represents the bottom plate element which comprises a single sheet of metal,

glass, plastic or other material, formed in the manner shown to provide annular concentric troughs 22 and crests 24 and openings 26 for downspout (not shown). Perforations 28 are provided in crests 24.

Top plate element 30 likewise comprises a single sheet formed in the manner shown to produce corresponding annular concentric troughs 32 and crests 34. The troughs 32 in their lower portions are provided with perforations 36.

It is important that perforations 28 in bottom plate are at a higher level than the corresponding perforations 36 in top plate in order that a liquid seal may be maintained upon the tray.

The top plate element 30 may be fastened to bottom plate element 20 in any suitable manner, such as by welding, bolting, riveting, etc., at appropriate points, such as welding plate 30 to plate 20 at the periphery of the former, or bolting plate 20 and plate 30 at points along 32 and 22 with or without spacers (not shown) to maintain a vertical clearance between these portions of plate elements 20 and 30, as explained below.

In Figure II, 38 represents the column wall to which is fastened the bottom plate element 20 by welding or other suitable means. Plate element 20 is provided with downspout 40, and carries top plate element 30 described above.

In Figure V, troughs 32 are provided with perforations 36 which may vary in size and are disposed in such manner that the jets of gas emerging therefrom do not converge, and in which the perforation sizes vary to make allowance for differences in pressure with respect to their height. When employing top plate elements with perforations of this type, it is preferable that there be some clearance between the crests 24 of plate 20 and the troughs 32 of plate 30, in order that there is a gas passage to the bottom holes 36.

In operation of a column built upon this plan, liquid collects above the trays at a level determined by the level of the edge of downspout 40 above the tray and flows from the point of entrance below the downspout from the plate above, across the plate through downspout 40 to the plate below. The vapors or gas pass up the column through perforations 28 and 36 in the plates, thus forming jets of gas which intimately contact the liquid as it flows across the plate. The height of the edge of downspouts 40 and 40' above the level of the tray has been exaggerated in Figure III for purposes of simplicity and to indicate clearly that a liquid seal is present. However, in practice, except when dealing with high vapor velocities, the level of the downspout 40 would be about the same as, or only slightly higher than, the level of the perforations 28 in the bottom plate. Gas is prevented from flowing up through the downspouts by the fact that they terminate at a point beneath the liquid level of the tray which they feed.

In Figure VI, which represents a top view of another type of tray according to the present invention. (B of Figure VII represents the tray described herein except where otherwise indicated) 42 represents the top plate element which comprises a single sheet of metal, glass or other material, formed in the manner shown to produce parallel spiral troughs 44 and crests 46 originating near the center and terminating near the periphery of the tray, provided with downspout 48. Perforations 50 are provided in the troughs 44 (for simplicity, only a portion of these perforations 48 have been indicated). Plate element 42 is fastened to column wall 52 in any

suitable manner. 54 represents the area upon the tray B where the liquid from the tray A above enters the tray B through the downspout bounded by wall 56, dam 58, column wall 52 and spiral baffle 60.

Spiral baffle 60 is fastened to the crests as shown by spot welding or other means, one end being fastened to downspout 48 while the other is fastened to column wall 52 at point 62. Thus baffle 60, plate 56 and column wall 52 bound area 64.

In Figure VII area 66 is cut from downspout 48 so that the upper portion is the same height as baffle plate 60 while the distance between the tray and the edge of the lower portion of the cut serves as a dam to regulate the depth of the liquid maintained on the tray. Area 67 is cut from the bottom of downspout 48 to admit liquid from the tray above and to direct the flow into the spiral path. The rest of the bottom edge of downspout 48 contacts the plate it feeds and may be fastened thereto, if desired, although this is generally not necessary.

It may be observed that the center of the plates is alternately the downspout or the receiving area, depending upon its relationship to the plate above. In plate A the central area 68 is not cut out, but the area 54 at the periphery is cut out to carry the downspout bounded by and comprising column wall 52, dam 58 and a vertical extension (not shown) of spiral baffle 60 between wall 56 and dam 58 and a vertical extension (not shown) of wall 56, while in plate B the central area 66 is cut out to carry downspout 48 while the liquid is admitted to the plate or area 54 which is solid, and thus there is no vertical extension of wall 56 or the portion of spiral baffle 60 between 56 and 58. Tray C is similar to tray A, etc. Weep holes 70 are provided at the base of plate 56 to drain to the downspout any liquid collected in area 64. Upon trays which have the central area cut out (e. g., B) wall 56 may be dispensed with entirely if desired.

In Figure VIII, which is a bottom view of tray B (as of Figure VII), 52 represents the column wall to which is attached bottom plate element 72, which likewise comprises a single sheet of material, formed in the manner shown to produce a series of parallel spiral troughs 74 and crests 76. The crests 76 are provided with perforations such as slots 78. The area 68 is cut out to carry downspout 48. The dotted line 80 represents the portion cut out in case the tray were one higher or one lower than shown (that is, A or C as of Figure VII). In the latter case, the central portion 68 is left solid.

In operation of a tray built according to this type, the liquid condensate collects upon the tray and flows in a spiral path over the tray as the gases or vapors bubble through it. The liquid level is maintained about at the level of the crests by the dams, although the foam above it may be 2 to 3 times or more higher. The baffle 60 forces the foam as well as the liquid to follow the elongated spiral path. The object of increasing the length of the path of flow across the tray is to increase the degree of contact and fractionation efficiency. The liquid flows across one tray A down through the downspout at the periphery to the periphery of the tray below B along the spiral path to the center of the tray, thence to the center of the tray below C and thence along the spiral path to its periphery, etc.

Although the downspout arrangement has been shown so that flow is from the periphery to the

center, to the center of the tray below to its periphery, etc., other types of flow, such as from periphery to center, to the periphery of the tray below to the center of that tray, etc., can be used by a suitable downspout system without departing from the spirit of the present invention. Likewise, it is within the scope of this invention to reverse the spirals of alternate trays or to vary the differences in distance between trays, as desired.

In Figure X top plate element 80 is provided with downspout apertures 82 and individual elevated portions 84 provided with perforations 86.

Figure XI shows a cross section of the tray of Figure X in which the bottom plate element is represented by 88 and a perforation therein by 90.

In Figure XII, 92 represents the column wall to which is attached upper plate element 94. Plate element 94 comprises a single sheet formed in the manner shown to provide spiral raised crests 96 and troughs 98, provided with perforations 100 near the bases of the troughs. The spiral troughs descend from the apex around an imaginary cone terminating in a downspout at the periphery as indicated.

Upper plate 94 carries lower plate 102 comprising a corresponding spiral cone provided with crests 104 and troughs 106, registering with the corresponding crests and troughs of the upper plate. Crests 104 are provided with perforations 108. Plate elements 94 and 102 co-act to form tray A.

Tray B comprises top plate element 110 and bottom plate element 112. Top plate element 110 is fastened to column wall 92 and likewise comprises a series of crests 114 and troughs 116, the latter of which are provided with perforations 118 near their bases. Plate element 110 carries bottom plate element 112, which comprises corresponding spiral troughs and crests 120 and 122, respectively. The crests are provided with perforations 124. The spiral troughs in tray B originate at a point directly under the downspout of plate A at the periphery and descend around an imaginary inverted cone, terminating at the apex.

In top plate element 94, at the point where the spiral trough fades into the column wall, is provided an opening for a downspout, comprising wall 126 and end plates 128 and 130 (see Figures XIII—XIV) which, with wall 92, bound the downspout and terminate at the bottom in opening 132. On lower top plate element 110 are provided dams 134 and 136 to provide a seal for the downspout of the plate above. Plate element 110 is also provided with a central downspout pipe 138, which may be an integral part of plate elements 110, at the terminus of the spiral trough at the central lower portion of the cone to feed the plate below.

In normal operation of a tray built according to this type, liquid reflux is fed upon the apex of the tray A and flows in a spiral path down over the tray as the ascending gases or vapors bubble through it. The liquid flows from the center of one tray around a descending spiral to the periphery, down through the downspout to the periphery of the tray below, around in a spiral, terminating at the center and thence to the center of the tray below to its periphery, etc. A column of this type is especially useful when dealing with high reflux ratios and it is important that sufficient liquid head be maintained so that the liquid does not run away from the heights to the lower

portions of the tray, leaving free gas passage without the necessity of bubbling the vapor through liquid. Gas is forced to pass up through the liquid and not up the downspouts by the seals provided at the points where the downspouts terminate in the plates below.

Although the drawings show that the spirals encompass a cone, it is only necessary that the origin of the spirals and their terminals be upon different levels, so that the flow by going downward is accelerated to overcome fluid friction. Likewise it is not necessary that the alternate cone-like spiral plates be inverted, since with a suitable downspout system they may be all disposed in the same manner.

The tray construction of the present invention is adapted for use in any type bubble tower or fractionating tower consisting of a vertical and preferably cylindrical vessel, varying in diameter and height according to the specific work to be done, the volume of vapors to be handled and the degree of fractionation necessary.

A bubble or fractionating tower is equipped either centrally or near its lower portion with a vapor inlet line and a vapor outlet line near the top of the tower. Means may be provided for the supply of liquid condensate to the top of the tower or closed coils may supplement the trays to increase fractionation of the vapors. In the bottom of the tower is a liquid draw-off line.

Of the above, details with reference to operating requirements of the tower itself have been eliminated from the drawings for simplicity, since the structural requirements for bubble towers have long been well known to the art, particularly with reference to the fractionation of oils, alcohols, etc.

Although no drawing shows more than three trays, it will be understood that any number of trays may be positioned in the tower according to the requirements of a particular installation.

In some of the drawings, for simplicity a portion of the perforations has not been shown. It is to be understood that perforations are distributed all over the trays in accordance with the invention.

In general, it is preferable that the trays should be so designed that the downspout area comprises from 10% to 30% of the cross sectional area of the column, while the bottom plate perforations comprise from 5% to 20% of this area, and the top plate perforations from 7% to 15% of this area. It is understood, however, that substantial variations from these figures may be required for special cases.

The optimum depth of the liquid upon the tray depends upon the vapor velocity through the column and in general the higher the vapor velocity the greater the depth of the liquid that should be maintained upon the tray. Under ordinary circumstances a liquid level approximately the same as the level of the perforations in the bottom plate is satisfactory.

Although only two variations of cross tray flow have been shown, that is, flow from periphery to periphery with an axis parallel to the diameter and spiral flow, it is to be understood that other baffle systems may be employed to increase the length of the path of flow across the plate. However, this type plate construction is especially well adapted to spiral flow and such a spiral tray is a preferred modification of the present invention.

Although the baffle 60 has been represented in the drawings as a separate piece of metal fas-

tened to the crests 46, it is to be understood that the invention also contemplates baffles which are integral parts of the plate elements comprising raised portions which are higher than adjacent crests.

Another advantage of the spiral or concentric trough and crest construction is the ability of such members to withstand tendencies to buckle and warp due to thermal expansion and contraction that occur with changes in temperature.

When dealing with spiral trays according to the present invention, it is best that the length of the spiral path be not greater than about ten times the diameter. Otherwise, pressure drop due to frictional resistance of flow across the tray may be sufficient to cause channeling. Spirals of approximately the proportions shown in the drawings, wherein the path is between about 4 and 6 diameters, are preferred, the drop in pressure due to friction being practically negligible and no channeling occurring.

Although the plate elements of my bubble trays, as described, may be fabricated in several pieces, for example, in halves, quarters, sixths, etc., and these parts welded, bolted, or otherwise fastened together, sometimes it is preferable to fabricate the entire plate element as a whole to cover the entire cross sectional area of the column. In this case the trays produced are of extremely simple construction, consisting of but three elements, a downspout (the portion of which extends above the plates serving as a dam to regulate the depth of liquid upon the tray), and the co-acting bottom and top plate elements. The top and bottom plate elements of such a tray can be stamped, cast, molded, drop or hydraulic forged, in one operation and the entire tray be completed by simply fastening the top element to the bottom element and welding or otherwise fastening the downspout in the aperture provided.

In cases where the raised elements are parallel, the tray can be fabricated by bending either with or without the application of heat and the trough ends covered by fastening a separate sheet of metal thereon.

Trays according to the present invention are especially well adapted to be cold stamped from relatively thin sheet metal. Trays can be made up to 4 feet or more in diameter of sufficient strength to withstand all the stresses of ordinary operation, although, if desired, supporting members such as angle irons and the like can be used to reinforce them. This is especially desirable with trays of larger diameter. By stamping heated metal sheets or forging, considerably thicker plates may be used.

The present invention has been described with the aid of simplified drawings; however, it should be understood that it may be embodied in other forms without departing from the spirit thereof. This is especially true with regard to the arrangement, distribution, size, shape, depth and contour of the raised portions upon the plate elements and the materials from which they are made; and also with respect to the distribution, size and shape of the perforations therethrough. It is only necessary that the top plate elements and the bottom plate elements be made of continuous sheets and be provided with elevated portions which correspond in arrangement although they may differ in shape and are so positioned that the perforations at the lowest level in the bottom plate are at a higher level than the corresponding perforations at the highest level in the top plate,

so that a liquid seal may be maintained upon the plate.

I claim as my invention:

5. In a bubble column a bubble tray comprising a continuous top plate element and a continuous bottom plate element, said elements being formed to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said crests, and said perforations in said crests are at a higher lever than said perforations in said troughs.
10. In a bubble column a bubble tray adapted to compensate for thermal expansion and contraction comprising a continuous top plate element and a continuous bottom plate element, said elements being formed to provide a series of corresponding concentric crests and troughs, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
15. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
20. In a bubble column a bubble tray comprising a continuous top plate element and a continuous bottom plate element, said elements being formed to provide a series of corresponding concentric crests and troughs, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
25. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
30. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
35. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
40. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
45. In a bubble column a stamped bubble tray comprising a continuous top plate element and a continuous bottom plate element, said elements being stamped to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
50. In a bubble column a stamped bubble tray comprising a continuous top plate element and a continuous bottom plate element, said elements being stamped from a single sheet of 16 gauge or thinner gauge metal to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
55. In a bubble column a stamped bubble tray comprising a continuous top plate element and a continuous bottom plate element, said elements being stamped from a single sheet of 16 gauge or thinner gauge metal to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
60. In a bubble column a stamped bubble tray comprising a continuous top plate element and a continuous bottom plate element, said elements being stamped from a single sheet of 16 gauge or thinner gauge metal to provide a series of corresponding alternate crests and troughs arranged in banks around a centrally located point of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs.
65. In a bubble column a bubble tray comprising a top plate element and a bottom plate element, said elements being formed to provide a series of corresponding spiral shaped alternate crests and troughs originating near the center and terminating near the periphery of said tray, said top plate element being superimposed on said bottom plate element so that said crests and troughs are in vertical alignment, said top plate element having perforations therethrough within the area of said crests, and said bottom plate element having perforations therethrough within the area of said troughs.
70. In a bubble column a bubble tray comprising a top plate element and a bottom plate element, said elements being formed to provide a series of corresponding spiral shaped alternate crests and troughs originating near the center and terminating near the periphery of said tray, said top plate element being superimposed on said bottom plate element so that said crests and troughs are in vertical alignment, said top plate element having perforations therethrough within the area of said crests, and said bottom plate element having perforations therethrough within the area of said troughs.
75. In a bubble column a bubble tray comprising a top plate element and a bottom plate element, said elements being formed to provide a series of corresponding spiral shaped alternate crests and troughs originating near the center and terminating near the periphery of said tray, said top plate element being superimposed on said bottom plate element so that said crests and troughs are in vertical alignment, said top plate element having perforations therethrough within the area of said crests, and said bottom plate element having perforations therethrough within the area of said troughs.

tions in said crests are at a higher level than said perforations in said troughs.

6. In a bubble column a bubble tray comprising a top plate element and a bottom plate element, said elements being formed to provide a series of corresponding spiral alternate crests and troughs originating near the center and terminating near the periphery of said tray, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs, and a corresponding vertical spiral baffle aligned in conformity with said spiral crests and troughs and fastened thereto.

7. In a bubble column of circular cross-section tray comprising a top plate element and a bottom plate element, said elements forming a series of corresponding spiral crests and troughs originating near the center and terminating near the periphery of said tray to provide a spiral path for liquid, said top plate element being superimposed on said bottom plate element so that said crests and troughs are in vertical alignment, said top plate element having perforations therethrough within the area of said troughs, said bottom plate element having perforations therethrough within the area of said crests, and said perforations in said crests are at a higher level than said perforations in said troughs and

the length of said path being not greater than 10 diameters of said tray.

8. In a bubble column a bubble tray comprising a continuous top plate element and a continuous bottom plate element, said elements being formed to provide a series of corresponding spiral alternate crests and troughs originating near the center and terminating near the periphery of said tray, said top plate element being superimposed on said bottom plate element so that said crests and troughs are in vertical alignment, said top plate element having perforations therethrough in said troughs, said bottom plate elements having perforations therethrough in said crests, and said perforations in said crests are at a higher level than said perforations in said troughs and the origins of said spirals being at a different level from that of the terminations of said spirals.

20 9. In a bubble column a bubble tray adapted to compensate the thermal expansion and contraction comprising a continuous top plate element and a continuous bottom plate element, said elements being formed to provide a series 25 of corresponding concentric polygonal crests and troughs, said top plate element being superimposed on said bottom plate element so that said crests and troughs are in vertical alignment, said top plate element having perforations there- 30 through within the area of said troughs, said bottom plate element having perforations therethrough within the area of said crests, and said perforations in said crests are at a higher level than said perforations in said troughs.

EMMETT L. DURRUM.
